DESIGN FOR A HAT

Arthur J. Stack, Westport, Conn., and Simone Olivan, New York, N. Y., assignors to Hat Corporation of America, Norwalk, Conn., a corporation of Delaware

Application June 27, 1941, Serial No. 101,732

Term of patent 3½ years

To all whom it may concern:

Be it known that we, Arthur J. Stack and Simone Olivan, citizens of the United States, residing respectively at Westport, in the county of Fairfield and State of Connecticut, and at New York, in the county of New York and State of New York, have invented a new, original, and ornamental Design for a Hat, of which the following is a specification, reference being had to the accompanying drawing, forming a part thereof, and in which—

Figure 1 is a top perspective view of a hat embodying the design.

Fig. 2 is a slightly perspective side view of the hat shown in Fig. 1.

The hat is characterized by a brim having a front outer portion sharply turned down in a generally vertically extending direction and by a crown having an upwardly, forwardly and generally convex curving rear wall portion, said crown having a simple and slightly raised top portion, and said crown having a diametrical length several times its height, all as shown.

We claim:

The ornamental design for a hat, as shown and described.
